[57] ABSTRACT

Disclosed herein is a marine propulsion device comprising an engine starter including a rotatably mounted shaft and a pinion carried by the shaft for movement relative to the shaft and relative to an engaged position in mesh with an engine starting gear, and cooperating, selectively operable means on the shaft and pinion for displacing the starter pinion to the engaged position in response to shaft rotation and for preventing movement of the starter pinion to the engaged position, notwithstanding shaft rotation. In one embodiment, there is included a linkage connecting the selectively operable means to a transmission shiftable between a neutral condition and a drive condition and operable to selectively operate the cooperating means on the shaft and the pinion for displacing the starter pinion to the engaged position and for preventing movement of the starter pinion to the engaged position.

ENGINE STARTER MECHANISM

BACKGROUND OF THE INVENTION

The invention relates generally to starter mechanisms for internal combustion engines, such as are included in marine propulsion devices having reversing transmissions. In the past, it has been sometimes possible to initiate engine starting operation when the transmission is in gear. Such operation is undesirable for various reasons including the possibility of sudden lurching of the boat supported by the marine propulsion device.

One previous arrangement for preventing engine starting operation by a starter when a reversing transmission is in a drive condition is found in the U.S. Berry and Dubois Pat. application Ser. No. 156,227, filed June 24, 1971.

Another example of a previous arrangement for preventing engine starting operation when a reversing transmission is in a drive condition is found in the U.S. Russey et al. Pat. No. 2,997,996, issued Aug. 29, 1961.

SUMMARY OF THE INVENTION

The invention provides a marine propulsion device which includes an engine starting gear, a reversing transmission, and a starter mechanism including a rotatable starter shaft and a starter pinion carried on the starting shaft for movement relative to the starter shaft and to an engaged position in mesh with the starting gear, together with selectively operable, cooperating means on the starter shaft and on the starter pinion for displacing the starter pinion to the engaged position in response to rotation of the starter shaft and for preventing movement of the starter pinion to the engaged position, notwithstanding rotation of the starter shaft.

Also in accordance with the invention, the reversing transmission is shiftable between a neutral condition and a drive condition and there is included means connecting the transmission to the selectively operable, cooperating means on the starter shaft and on the starter pinion for displacing the starter pinion to the engaged position in response to starter shaft rotation when the transmission is in neutral condition and for preventing displacement of the pinion to the engaged position when the transmission is in drive condition.

When the preferred embodiment of the invention includes control of the operation of the starter mechanism in accordance with the condition of the reversing transmission, it is within the scope of the invention to provide a control for the starter mechanism independently of the reversing transmission.

In one preferred embodiment of the invention, the means for displacing the starter pinion to the engaged position and for preventing movement of the starter pinion to the engaged position includes provision on one of the starter shaft and starter pinion of a drive pin and provision in the other of the starter shaft and starter pinion of a slot which receives the drive pin and which includes a portion extending axially of the starter shaft axis, and a portion extending in inclined relation to the starter shaft axis.

In this last regard, when the drive pin is in the axially extending slot portion, rotation of the starter shaft is ineffective to advance the starter pinion to the position engaging the starting gear as rotation of the starter shaft merely causes common rotation of the starter pinion. However, when the drive pin is in the inclined slot portion, rotation of the starter shaft will cause, because

of frictional restraint to rotation of the starter pinion with the starter shaft, axial displacement of the starter pinion relative to the starter shaft so as to arrive at the position in engagement with the starting gear. Thereafter, continued rotation of the starter shaft will cause rotation of the starter pinion and consequent rotation of the starting gear to initiate engine operation.

Still more particularly, one preferred embodiment of the invention includes employment of a starter shaft including an axial bore, together with a linkage operable in the bore to displace the starter pinion relative to the starter shaft so as to selectively locate the drive pin in either the axial or inclined slot portions. Preferably, the linkage includes a push rod movable axially in the starter shaft bore between a first or upper position locating the starter pinion such that the drive pin is located in the axially extending slot portion and a second or lower position in which the drive pin is located in the inclined slot portion.

The linkage further includes means connecting the push rod to the starter pinion so as to afford starter pinion movement in accordance with movement of the push rod, together with means for displacing the push rod in the bore of the starter shaft.

In one preferred embodiment of the invention, such means comprises a second push rod which is located in the starter shaft bore in engagement with the first push rod to afford axial displacement of the first push rod in response to axial displacement of the second push rod while permitting rotational movement therebetween, together with means for displacing the second push rod axially of the starter shaft bore.

In one preferred embodiment of the invention, the means for displacing the second push rod axially of the starter shaft bore comprises a pivotally mounted control shaft and a link pivotally connected between the second push rod and the control shaft so as to displace the second push rod within the starter shaft bore in response to rocking of the control shaft.

Still further in one preferred embodiment of the invention, the control shaft comprises a control shaft for the reversing transmission and the components are arranged such that the push rods are displaced to locate the drive pin in the axially extending slot portion of the starter pinion to prevent starter pinion movement to the position engaging the starting gear whenever the reversing transmission is shifted to a drive condition. However, the linkage is such that when the reversing transmission is located, by reason of movement of the control shaft, in the neutral condition, the second or lower push rod is so positioned so as to permit the first or upper push rod and the starter pinion to fall to a position in which the drive pin is located in the inclined slot portion so as to thereby afford advancement of the starter pinion to the position in meshing engagement with the starting gear in response to rotation of the starter shaft in the proper direction.

The invention also provides a starter mechanism which is adapted to be operatively connected to an engine and which includes various of the features already mentioned.

One of the principal objects of the invention is the provision of a starter mechanism including selectively operable, cooperating means on a starter shaft and on a starter pinion carried on the starter shaft for relative movement therebetween, which cooperating means is selectively operable to displace the starter pinion to a

position in meshed engagement with a starting engine gear in response to rotation of the starter shaft in one direction and for preventing such movement in response to such starter shaft rotation.

Another of the principal objects of the invention is the provision of a starter mechanism of the type referred to in the preceding paragraph, which starter mechanism is controlled so as to permit movement of a starter pinion to a position engaged with an engine starting gear and to prevent such movement in response to the condition of a reversing transmission.

Still another of the principal objects of the invention is the provision of a marine propulsion device including a starter mechanism which is operable to initiate engine starting only when the reversing transmission is in neutral, and which includes various of the features already mentioned.

Still more particularly, another of the principal objects of the invention is to afford starting operation of a starter mechanism when a reversing transmission is in neutral and to prevent starting operation of a starter mechanism when the reversing transmission is in a drive condition by means operable within a bore provided in a starter shaft.

Other objects and advantages of the invention will become known by reference to the following description, claims, and accompanying drawings.

DRAWINGS

FIG. 1 is a side elevational view of an outboard motor embodying various of the features of the invention.

FIG. 2 is an enlarged view of a portion of a mechanism shown in FIG. 1.

FIG. 3 is a fragmentary elevational view of various of the components of the mechanism shown in FIG. 3 with the pinion shown in its intermediate position.

FIG. 4 is a fragmentary elevational view of various of the components of the mechanism shown in FIG. 2 with the pinion shown in its locked-out position.

FIG. 5 is a fragmentary, partially broken away, top view of the mechanism shown in FIG. 2.

Before explaining the invention in detail, it is to be understood that the invention is not limited in its application to the details of construction and arrangement of parts set forth in the following general description or illustrated in the accompanying drawings, since the invention is capable of other embodiments and of being practiced or carried out in various ways. Also, it is to be understood that the phraseology or terminology employed herein is for the purpose of description and not of limitation.

GENERAL DESCRIPTION

Shown in the drawings is a marine propulsion device which embodies various of the features of the invention, which can take various forms and which, in the illustrated construction, is in the form of an outboard motor 11. Included in the outboard motor is a propulsion unit 13 comprising a powerhead 17 and a lower unit 21. The powerhead 17 includes an engine block 23 including a starting or flywheel gear 27 and a starter or starter mechanism 29 mounted on the engine block 23 and adapted to be actuated so as to engage the starting gear 2 and rotate the engine to initiate operation.

The lower unit 21 includes a portion which is normally under water, which rotatably supports a propeller 31, and which includes a clutch or reversing transmis-

sion 33 shiftable between a neutral condition and each of a forward drive and a rearward drive condition.

The transmission 33 is operated by a control rod 37 which extends vertically in the lower unit 21, which is operatively connected at its lower end to the reversing transmission 33, and which, at its upper end, emerges in proximity to the engine block 23. At its upper end, the control rod 37 is pivotally connected to the outer end of a lever 39 mounted on one portion of a suitably rotatably supported shift control shaft 41 which, at one end, extends exteriorly of a powerhead cover 43 and is adapted to be operated, i.e., rocked so as to actuate the transmission 33, either manually or by remote means connected thereto.

As thus far described, the construction is conventional and known in the art.

The starter mechanism 29 includes a mounting bracket 47 which is connected to the engine block 23 and which includes a vertically extending bore 49 carrying a starter drive shaft 51. Carried by the starter drive shaft 51 for rotary and axial movement relative thereto, is a starter pinion 53 which, in accordance with the invention, is movable between a first or engaged or advanced position in mesh with the starting gear 27, a second or partially advanced or intermediate position (See FIG. 3) below the engaged position and out of engagement with the starting gear 27, and a third or retracted or lock-out position (See FIG. 4) which is located below the intermediate position.

Means are provided for rotating the starter shaft 51 to enable displacement of the starter pinion 53 to its engaged position from its intermediate position and, when the starter pinion 53 is engaged with the starting gear 27, for initiating engine operation. Various arrangements can be employed. In the illustrated construction, such means comprises connection of the lower end of the starting shaft 51 to a pulley 57 which, in turn, has anchored thereto a pull rope (not shown).

The upper end of the starter shaft 51 is fixedly connected to a recoil spring 59 which is housed in a recess 61 in the mounting bracket 47 and has its other end anchored to the mounting bracket 47. Thus, in operation, when the pull rope is pulled, the starter shaft 51 initially rotates in a first or counterclockwise direction as viewed from the pinion end, as indicated by the arrow 67 in FIG. 2 to thereby coil the spring 59. Subsequently, the recoil spring 59 uncoils or unwinds, and thereby rotates the starter shaft 51 in the clockwise direction as shown by the arrow 63 in FIG. 2 and simultaneously rewinds the pull rope on the pulley 57. Other means can be employed within the scope of the invention for rotating the starter shaft 51.

In accordance with the invention, cooperating selectively operable means on the shaft 51 and on the pinion 53 are provided for preventing movement of the starter pinion 53 from the retracted position (See FIG. 4) to the engaged position when the starter pinion is in the retracted position, notwithstanding rotation of the starter shaft 51 in the counterclockwise direction, and when the starter shaft 51 is in the counterclockwise direction, and when the starter pinion 53 is in the intermediate position, for effecting movement of the starter pinion 53 from the intermediate position (See FIG. 3) to the engaged position in response to rotation of the starter shaft in the counterclockwise direction. While various arrangements can be employed, in the illustrated construction, such means comprises formation of the starter pinion 53 with a hub 69 having diametrically op-

posed slots 71 which are respectively located on opposite sides of the hub 69 and which respectively include an axially extending lock-out portion 73 and an axially inclined and circumferentially extending portion 77 extending from the lower or bottom end of the axially extending portion 73, together with a drive pin 79 which extends fixedly and diametrically from the starter shaft 51 and has opposite ends received in the slots 71. A single slot together with a drive pin having a single end received in the slot is within the scope of the invention, as well as location of the slot in the shaft and employment of a pin extending from the pinion into the slot in the shaft.

The slots 71 and drive pin 79 are arranged such that, when the starter pinion 53 is located in the before-mentioned fully retracted or lock-out position (See FIG. 4), the drive pin 79 is located at the upper end of the axially extending slot portions 73 and rotation of the starter shaft 51 will cause common rotation of the starter pinion 53 therewith in both rotative directions, but will be ineffective to advance the starter pinion 53 toward the engaged position.

However, when the starter pinion 53 is in the intermediate position (See FIG. 3), the drive pin 79 is located at or in the upper end of the inclined slot portions 77 and rotation of the starter shaft 51 in the counterclockwise direction will result in movement of the starter pinion 53 from the intermediate position (FIG. 3) to the engaged position, followed by starting rotation of the engine. Rotation of the starter shaft 51 in the opposite, or clockwise direction, will merely cause common rotation of the starter pinion 53 with the starter shaft 51.

Rotation of the starter shaft 51 in the counterclockwise direction, together with receipt of the drive pin 79 in the inclined portions 77 of the slots 71, causes advancement of the starter pinion 53 from the intermediate position (See FIG. 3) to the engaged position due to cooperating assistance from a drag spring 81 which includes a circular portion 83 engaged in an angular groove on the starter pinion 53 and which further includes an extending portion 87 which engages a suitable ear or stop 89 extending from the mounting bracket 47. Because of the frictional drag imposed by the spring 81 against common rotation of the starter pinion 53 with the starter shaft 51, initial rotation of the starter shaft 51 in the counterclockwise direction causes advancement of the starter pinion 53 from the intermediate to the engaged position. As is usual, ignition of the engine will cause engine operation at a rotational speed much in excess of the rotational speed of the starter pinion 53 and thereby serves to cause retraction of the starter pinion 53 from the engaged position toward the intermediate position.

In accordance with the invention, a linkage or means 89 is connected to the just described selectively operable means to afford selective operation thereof. While other arrangements can be employed, in the illustrated construction, the starter shaft 51 is hollow or includes a bore 90 and there is provided in the hollow interior or bore 90 an upper push rod 91 which is movable between upper and lower positions and means for connecting the push rod 91 to the starter pinion 53 to afford starter pinion movement in accordance with push rod movement. While various means can be employed, in the illustrated construction, such means includes a lift pin 93 extending fixedly from the upper push rod 91

through diametrically opposite axially extending openings 97 in the starter shaft 51 and into engagement with the under surface of the starter pinion 53. When the upper push rod 91 is in its lower position, the starter pinion 53 is free to automatically fall or descend on the starter shaft 51, under the influent of gravity, from the intermediate or engaged positions to the retracted or lock-out position (See FIG. 4) with the lower face of the starter pinion 53 engaged with the lift pin 93, to thereby locate the drive pin 79 at the upper end of the axially extending slot portion 73. As already indicated, when the drive pin 79 is in the axially extending slot portion 73, rotation of the starter shaft 51 will result only in common rotation of the starter pinion 53, without any advancement of the starter pinion 53 toward the position in engagement with the starting or flywheel gear 27.

When the upper push rod 91 is in its upper, raised or elevated position, the push rod lift pin 93 will support the starter pinion 53 in its intermediate position. Similarly displacement of the upper push rod 91 from its lower to its upper positions will raise the starter pinion 53 from its retracted or lock-out position to its intermediate position.

The means for effecting selective operation further includes means for displacing the upper push rod 91 within the hollow interior of the starter shaft 51 from the lower position to the upper position so as to locate the starter pinion 53 in the intermediate position with the drive pin 79 at the top end of the inclined slot portion 77 and for permitting the upper push rod 91 to fall, under the influence of gravity, from its upper position to its lower position, and thereby to also permit the starter pinion 53 to fall from its intermediate position to its retracted or lock-out position. While various arrangements can be employed, in accordance with the illustrated construction, the lower end of the hollow interior of the starter shaft 51 is open and there is received therein a second or lower push rod 121 which, at its upper end, engages the bottom of the upper push rod 91 so as to control the position thereof while permitting rotation of the upper push rod 91 with the starter shaft 51 relative to the lower push rod 121. At its other or lower end, the lower push rod 121 is pivotally connected, about an axis transverse to the axis of the starter shaft 51, to an arcuately extending connecting link 123 which, in turn and at its lower end, is pivotally connected to a lever 127 extending fixedly from the pivotally mounted shift control shaft 41.

The components are so arranged so that when the shift control shaft 41 is in its neutral position, the lower push rod 121 is located in its most elevated position within the starter shaft 51, thereby raising the upper push rod 91 to its upper position, which, in turn, raises the starter pinion 53 on the starter shaft 51 to the intermediate or partially advanced position with the drive pin 79 located in the upper end of the inclined slot portion 77. Accordingly, with the components in the just described position, rotation of the starter shaft 51 in the counterclockwise direction will cause advancement of the starter pinion 53 from the intermediate or partially advanced position to the fully advanced or engaged position to effect engine starting operation. It is to be especially noted that engine starting operation is permitted when the shift control shaft 41 is in the neutral position.

However, whenever the shift control shaft 41 is rocked from its neutral position to either of the forward or reverse drive positions, the linkage 89 serves to lower or partially withdraw the lower push rod 121, thereby permitting the lowering of the upper push rod 91 under the action of gravity to its lower position and simultaneously to afford lowering of the starter pinion 53 to the fully lowered or retracted lock-out position. As already explained, when in the fully lowered or retracted lock-out position, the drive pin 79 is located at the upper end of the axially extending slot portion 73 to thereby prevent starter pinion movement from the retracted toward the engaged position. Accordingly, whenever the shift control shaft 41 is rocked from its neutral position, the starter pinion 53 is permitted to fall to its lock-out position so as to prevent engine starting operation of the starter mechanism 29.

While the illustrated construction has included the shift control shaft 41 as a part of the means 89 for effecting selective operation of the starter pinion 53, various of the features of the invention can also be obtained when such means for effecting selective operation of the starter pinion includes a manually, or otherwise operable, shiftable shaft mechanism independent of the reversing transmission or of the shift control shaft 41.

Various of the features of the invention are set forth in the following claims:

1. A marine propulsion device comprising an engine having a starting gear, a starter including a rotatable starter shaft and a pinion carried on said shaft for movement relative to said shaft and to an engaged position in mesh with said starting gear, and selectively operable cooperating means on said shaft and on said pinion for displacing said pinion to said engaged position in response to rotation of said shaft and for preventing movement of said pinion to said engaged position notwithstanding rotation of said shaft.

2. A marine propulsion device in accordance with claim 1 wherein said means for displacing said pinion to said engaged position and for preventing pinion movement to said engaged position includes a drive pin on one of said shaft and said pinion and a slot in the other of said shaft and said pinion, said slot receiving said drive pin and including a portion extending axially of the axis of said shaft and a portion extending in inclined relation to the axis of said shaft.

3. A marine propulsion device in accordance with claim 2 wherein said shaft includes an axial bore therein and a linkage operable in said bore to displace said pinion relative to said shaft so as to selectively locate said drive pin in the axial and inclined slot portions.

4. A marine propulsion device in accordance with claim 3 wherein said linkage includes a push rod movable axially in said shaft bore, means connecting said push rod to said pinion to afford pinion movement in accordance with movement of said push rod, and means for displacing said push rod in said bore.

5. A marine propulsion device in accordance with claim 4 wherein said means for displacing said push rod comprises a second push rod in said shaft bore in engagement with said first mentioned push rod, and means for displacing said second push rod axially of said shaft bore.

6. A marine propulsion device in accordance with claim 5 wherein said means for displacing said second

push rod comprises a pivotally mounted control shaft and a link pivotally connecting said second push rod to said control shaft.

7. A marine propulsion device in accordance with claim 5 and further including a reversing transmission shiftable between a neutral position and a drive position and wherein said means for displacing said second push rod comprises linkage means connected between said reversing transmission and said second push rod and operable for preventing movement of said pinion to said engaged position when said reversing transmission is in said drive position and for affording movement of said pinion to said engaged position in response to shaft rotation when said reversing transmission is in the neutral position.

8. A marine propulsion device comprising an engine having a starting gear, a transmission shiftable between a neutral condition and a drive condition, a starter including a rotatable starter shaft and a pinion carried on said starter shaft for axial and rotative movement relative to said starter shaft, selectively operable means on said starter shaft and on said pinion for displacing said pinion relative to an engaged position in mesh with said starting gear in response to rotation of said starter shaft and for preventing movement of said pinion to said engaged position notwithstanding rotation of said shaft, and means connecting said transmission to said selectively operable means on said starter shaft and on said pinion for operating said selective means to displace said pinion to said engaged position in response to starter shaft rotation when said transmission is in neutral condition and for operating said selective means to prevent displacement of said pinion to said engaged position in response to starter shaft rotation when said transmission is in drive condition.

9. A marine propulsion device in accordance with claim 8 wherein said means for displacing said pinion to said engaged position and for preventing pinion movement to said engaged position includes a drive pin on one of said shaft and said pinion and a slot in the other of said shaft and said pinion, said slot receiving said drive pin and including a portion extending axially of the axis of said shaft and a portion extending in inclined relation to the axis of said shaft.

10. A marine propulsion device in accordance with claim 9 wherein said shaft includes an axial bore therein and a linkage operable in said bore to displace said pinion relative to said shaft so as to selectively locate said drive pin in the axial and inclined slot portions.

11. A marine propulsion device in accordance with claim 10 wherein said linkage includes a push rod movable axially in said shaft bore, means connecting said push rod to said pinion to afford pinion movement in accordance with movement of said push rod and means for displacing said push rod in said bore.

12. A marine propulsion device in accordance with claim 11 wherein said means for displacing said push rod comprises a second push rod in said shaft bore and means for displacing said second push rod axially of said shaft bore.

13. A marine propulsion device in accordance with claim 12 wherein said means for displacing said second push rod comprises a pivotally mounted control shaft and a link pivotally connecting said second push rod to said control shaft.

14. An engine starter including a rotatable starter shaft and a pinion carried on said shaft for movement relative to said shaft and relative to a position adapted for meshing engagement of said pinion with an engine starting gear when in said position, and a drive pin on one of said shaft and said pinion and a slot in the other of said shaft and said pinion and receiving said drive pin, said slot including a portion extending axially of the axis of said shaft and a portion extending in inclined relation to the axis of said shaft, whereby, when said drive pin is in said axially extending slot portion, said pinion is prevented from moving to said position and when said drive pin is in said inclined slot portion, said pinion is displaced to said position in response to rotation of said shaft.

15. An engine starter in accordance with claim 14 wherein said shaft includes an axial bore therein and a linkage operable in said bore to displace said pinion relative to said shaft so as to selectively locate said drive pin in the axial and inclined slot portions.

16. An engine starter in accordance with claim 15 wherein said linkage includes a push rod movable axially in said shaft bore and means connecting said push rod to said pinion to afford pinion movement in accordance with movement of said push rod.

17. An engine starter in accordance with claim 16 wherein said linkage further includes means for displacing said push rod in said bore.
